UNITED STATES PATENT OFFICE.

JOHN WILLIAM DILL, OF BRADDOCK, PENNSYLVANIA.

DESIGN FOR A BELT.

60,608.

Specification for Design. Patented Mar. 14, 1922.

Application filed July 15, 1921. Serial No. 485,116. Term of patent 14 years.

To all whom it may concern:

Be it known that I, JOHN WILLIAM DILL, a citizen of the United States of America, residing at Braddock, in the county of Allegheny and State of Pennsylvania, have invented a new, original, and ornamental Design for Belts, of which the following is a specification, reference being had to the accompanying drawings, forming a part hereof.

The figure is a plan view of a portion of the belt showing my new design.

I claim:

The ornamental design for a belt as shown.

JOHN WILLIAM DILL.
